(57) **CLAIM**

The ornamental design for a fold over seat mat, as shown and described.

DESCRIPTION

FIG. 1 is a perspective view of a fold over seat mat showing our new design in a closed configuration;

FIG. 2 is a front view of the fold over seat mat of FIG. 1 in a closed configuration;

FIG. 3 is a right view of the fold over seat mat of FIG. 1 in a closed configuration;

FIG. 4 is a left view of the fold over seat mat of FIG. 1 in a closed configuration;

FIG. 5 is a top view of the fold over seat mat of FIG. 1 in a closed configuration;

FIG. 6 is a perspective view of the fold over seat mat of FIG. 1 in an open configuration;

FIG. 7 is a front view of the fold over seat mat of FIG. 1 in an open configuration;

FIG. 8 is a right view of the fold over seat mat of FIG. 1 in an open configuration;

FIG. 9 is a left view of the fold over seat mat of FIG. 1 in an open configuration; and,

FIG. 10 is a top view of the fold over seat mat of FIG. 1 in an open configuration.

In FIGS. 1-10, broken lines indicate environmental structure that forms no part of the claimed design.

1 Claim, 10 Drawing Sheets
